(57) **CLAIM**

The ornamental design for a wireless lavalier microphone receiver, as shown and described.

DESCRIPTION

FIG. 1 is a perspective view of a wireless lavalier microphone receiver showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion "9" shown in FIG. 1. The dot-dash-dot broken lines encircling portions of the wireless lavalier microphone receiver in FIG. 1 and illustrated in the enlarged view of FIG. 9 forms no part of the claimed design.
